COLLAPSIBLE TABLE

Walter B. Craighead, St. Paul, Minn.

Application September 17, 1937, Serial No. 164,353

2 Claims. (Cl. 311—89)

My invention relates to collapsible tables of portable size and adaptable for use as a card table, picnic table and the like, the main object of the invention being to provide a lightweight yet sturdily constructed and collapsible table which when folded up requires but very little space.

Sectional legs are also included providing for setting up the table at different elevations and other unique and useful construction embodied in the device are hereinafter fully set forth, reference being had to the accompanying drawing, in which:—

Fig. 1 is a top view of the table opened up and including a checker-board field on the top surface.

Fig. 2 is an enlarged bottom view of Fig. 1 showing the legs folded flat and the rotatable under brace member for the table top sections 20 swung partly out of bracing position.

Fig. 3 is a perspective view of Fig. 2 modified to show the legs set up and the board bracing and holding means in operative position.

Fig. 4 is an edge view of the table collapsed, 25 looking as in the direction indicated by arrow 4 in Fig. 2.

Fig. 5 is an end view of the table almost completely collapsed as it would be seen from the bottom edge of Fig. 2.

Fig. 6 is a detail view of a modified form of 30 table leg which is sectional.

Fig. 7 is a side elevation of the table set up with the shortened type of legs.

Referring to the drawing by reference numbers, like characters designating corresponding parts in the various views: My table comprises a multi-leaf top including two center sections 1 and 2, hinged together as at 3 to break downwardly from original position.

40 4 and 5 are opposite outer top sections or leaves hingedly connected at their inner edges respectively to the outer edges of the center sections 1 and 2, as at 6, to break upwardly, said hinges 6 being on the under side of the table top.

45 The outer leaves 4 and 5 are necessarily wider than the center sections 1 and 2 to enable folding of the latter between the outer sections and provide clearance inwardly of the free edges of sections 4 and 5 where the table legs and connected parts are collapsed and lie against the under side of said parts.

50 7 and 8 designate two pairs of corresponding legs each pivotally mounted near a corner of the table top at its under side. The legs 7 are pivotally mounted at 9 at diagonally opposite corners

of the table each to an end part of a rib or box flange member 10 secured one to the under side of each outer leaf (4—5) parallel to and in spaced relation inwardly of its free edge. Said flanges 10 comprise two or the four sides of a quadrangular box-frame on the under side of the table top the other two sides of which comprise a pair of corresponding flanges 11 but which are hinged as at 12 to an end part of a flange 10 opposite from the hinge 9, to swing each parallel thereto and from thence outwardly to right angles with relation to its flange 10 and each having means for securing its free end in proximity to an end of the opposite flange 10 at which a leg 7 is pivoted. 15

In Fig. 3 the further flange 11 is positioned while the nearer one is shown in position about to be fixed with its free end near the right hand fixed flange 10. 20

The diagonally opposite legs 8 are each pivotally connected at 13 to the hinged end part of a flange 11 and when the table is to be collapsed or set up each leg 8 lies at inner side of and close to and parallel with a flange 10 (Fig. 2). Simultaneously the other pair of legs 7 lie each 25 parallel to a flange 10 at outer side of the latter.

Each leg is connected to its adjacent box flange preferably by a so-called and well known knee-brace 14, i. e. legs 7 each have such a brace connecting it with the adjacent fixed flange 10 in 30 such manner that when the leg is swung upwardly to right angular position relative to the top boards the knee brace is positioned angularly to hold the leg in said position but may be broken upwardly to enable the leg to be folded and lie 35 flat against the top board and parallel to the flange 10. The corresponding knee-braces 14 for the legs 8 are connected each as at 15A to the adjacent swingable box flange 11 (see Fig. 3). When the legs are folded up under the table top 40 the knee braces 14 are folded up in unobstructive position (see Fig. 2).

Fig. 6 is a partly sectional side elevation of a modified form of table leg which is made in two sections of which 16 is the outer section removably connectible with the pivoted section as by means of a preferably tapered dowel extension 17 of the latter and insertible frictionally in a corresponding bore of the outer leg section. Thus when the outer leg sections 16 are removed the 50 short main leg sections with their prongs 17 directed downwardly may be placed on the ground G (Fig. 7) the prongs pushed into the ground as shown and the table is rigidly set up with its top about 15 or 18 inches (approximate- 55

ly) over the ground, a desirable feature for picnic lunches when persons may be seated on the ground around the table. In other words the full length legs provide for a table of normal height and the shorter legs for purposes such as just described or for use of children.

In Fig. 1 the top area of the table is shown with a central checker board field 18.

19 in Figs. 2 and 3 designates a pivoted brace bar at the under side of the board, pivoted as at 20 as near as possible to the center line (between panels 1 and 2). When the table is folded up this bar must lie parallel to said center line as shown dotted in Fig. 2. However, when the table is to be set up and the top sections have been opened and put in a common plane, the brace is swung on its pivot to a position transversely of the top panels and its opposite ends engage in notches or cut-outs 10C of the opposite fixed box flanges 10. Obviously when this brace bar 19 is in its bracing position as shown in Fig. 3, the entire table top is rigidly braced at its under side.

In Fig. 3 is best shown a metal bracket 22 fixed to the under side of the table boards 4-5 one to each board at diagonally opposite corners and adjacent the pivot end of the legs 7. This brace comprises in part a rigid flange or inward projection 22F extending inwardly parallel to the under side of the table top. The free end part of each box-flange 11 is slotted longitudinally (Fig. 3) said slotted part to slidably engage the flange 22F of bracket 22 outwardly when the flange 11 is to be positioned at right angles to the adjacent flanges 10. The flange 22F then projects inwardly of flange 11 and exposing an aperture 23 and arranged to be engaged, removably, by a hook 24 pivotally mounted at the inner side of flange 11 adjacent its slit thus holding the box flange 11 in bracing position but very readily disconnected.

To collapse a table for shipping or storage purposes, the brace 19 is first put in dotted line position shown in Fig. 2, then the hooks 24 are disengaged, then the legs 8 are folded or swung toward the under side of the top to lie parallel to their respective flanges 11. Each flange 11 and its leg 8 are then swung over to lie parallel to the flange 10 to which the dual parallel members are hingedly connected at 12.

Then the legs 7 are folded down to lie parallel each to the outer side of the adjacent fixed flange 10. Then the center panels 1-2 are folded inwardly between the outer panels 4-5, as in Fig. 5 and said latter parts 4-5 pressed toward each other to inclose all the parts described between them.

The entire device when thus folded occupies a minimum of space, a standard size card table when thus folded comprising a package only about 3 inches thick, 32 inches long and 10 inches wide. The folded device obviously can be easily transported in a motor car, or stored in a closet or other convenient space.

The use of my collapsible table has been fully disclosed simultaneously with the description of its construction. It will be readily understood however that various modifications as to details of structure and proportions of parts may be made without departing from the scope and spirit of the invention. For example, the top panels may be of so-called ply-board, "Prest-wood" or any other material of suitable strength and preferably of light weight. Also, the extensible legs may be of tubular telescopic construction or any other mechanical equivalent.

I claim:

1. In a foldable table of the class described having a top formed of two like central panels and two wider outer panels all hinged together edge to edge to enable folding of the first two upon each other and the latter two upon the folded inner panels; a fixed longitudinal box flange parallel to the outer free edge of each outer panel at its under side, a leg pivotally connected to one end part of each said box flange and arranged to lie along the outer face of the flange, a combination leg and flange member pivotally secured to the opposite end of said fixed flange to lie initially in parallelism with the inner face of said flange, said combination member adapted to be swung to position at right angles to the fixed flange and traversing the extended top boards, and the leg part of said combination member pivotally connected to its flange member exteriorly of its hinge connection with the fixed flange, means for removably engaging and holding said movable flange at right angles to its fixed flange, and the leg member of said combination member adapted to be swung up to position at right angles to the under side of the sectional table top.

2. The structure specified in claim 1, in which said means for holding the free end of the swingable flange consists of the provision of a slit in the free end thereof, a flat metal clip fixed to the under side of the table top and formed with a flat offset flange in the path of and straddled by said slotted part of the swingable flange member, said offset flange provided with an aperture exposed inwardly of the flange when the latter is in outer position and a hook pivotally mounted on the inner face of said swingable flange to engage in said aperture.

WALTER B. CRAIGHEAD.
